UNITED STATES PATENT OFFICE

2,544,865

GRAIN DOOR

Corliss O. Thomas, Ralls, Tex.

Application May 10, 1948, Serial No. 26,141

2 Claims. (Cl. 160—210)

1

This invention relates to inside grain doors for freight cars, and the primary object of the invention is to provide novel mounting and counterbalancing means for the door so that it may be readily slid upwardly to release its lower end, and then swung inwardly and upwardly to an open position near the roof of the car to occupy a space extending from the adjacent side of the car to a point short of the longitudinal center thereof, whereby the open door will not interfere with the opening or closing of a similar opposing door in the other side of the car, even though the hanger rods of the door are longer than one-half the width of the car when the door is closed.

Another object of the invention is to provide novel means for releasably holding the door in open position and for firmly clamping it against lateral movement by a sudden jerking of the car, when open.

The exact nature of the present invention will become apparent from the following description when considered in connection with the accompanying drawings, in which:

Figure 1 is a fragmentary vertical longitudinal section of a freight car equipped with a grain door embodying the present invention, and showing the inner side of the door;

Figure 2 is a vertical transverse section taken on the line 2—2 of Figure 1;

Figure 3 is a horizontal section taken on the line 3—3 of Figure 2;

Figure 4 is a vertical transverse section taken on line 4—4 of Figure 1;

Figure 5 is a fragmentary horizontal section taken on line 5—5 of Figure 2;

Figure 6 is a fragmentary horizontal section taken on line 6—6 of Figure 1;

Figure 7 is a fragmentary horizontal section taken on line 7—7 of Figure 1;

Figure 8 is a fragmentary section taken on line 8—8 of Figure 4;

Figure 9 is a fragmentary elevation of the outer side of the lower section of the door, showing the wicket thereof.

Referring in detail to the drawings, 5 indicates a portion of a modern freight car having a side doorway 6 whose height is more than twice the distance from each side of the car to the longitudinal center thereof. In practice, a similar doorway (not shown) is provided in the other side of the car directly opposite the doorway 6.

In accordance with the present invention, each door jamb 6' is rabbeted as at 7 throughout the inner corner of its inner edge for reception of

5 a sealing strip 8 having a central longitudinal groove 9. The door is composed of a lower section 10, and an upper section 11 of slightly lesser vertical dimension and hinged at 12 to the lower section 10 for folding inwardly and downwardly against the inner face of the latter. The door sections are preferably constructed of sheet metal and suitably reinforced, as by horizontal angle bars 13 and vertical angle bars 14 secured to the 10 outer faces thereof. The vertical angle bars 14 are disposed adjacent the vertical edges of the door sections and have transverse flanges slidably fitting in the grooves 9 of the strips 8 to seal the door at the sides when closed and prevent 15 outward displacement thereof. Along the bottom of the doorway, the car floor 15 is grooved as at 16 to receive the lower edge portion of the lower door section when the door is closed, for the same purpose.

20 For hanging the door, I provide vertical hollow columns 17, and a hanger rod associated with each column and composed of telescopic lower and upper sections 18 and 19, respectively. The columns 17 are rigidly attached to and spaced 25 outwardly from the sides of the lower door section 10 out of the path of the door section 11 by means of brackets 20, and they extend from a point slightly above the plane of the lower edge of said door section 10 to the plane of the upper 30 edge thereof. Each rod section 18 slidably projects into the upper end of the associated column 17, and each rod section 19 slidably projects into the associated rod section 18, while the upper ends of the rod sections 19 are hinged at 35 21 to the inner side of the lintel beam 22 to swing vertically. To prevent separation of the elements 17, 18 and 19, the elements 18 and 19 have heads 23 and 24 on their lower ends adapted to contact bushings 25 and 26 secured in the upper ends of the elements 17 and 18, when said elements 18 and 19 are fully extended. Thus, the door may be slidably elevated to unseal the same at the bottom and to then collapse the rod sections 18 with respect to columns 17 and the rod sections 40 19 with respect to the rod sections 18, after the upper door section 11 is folded. While this collapsing action takes place, the folded door is swung upwardly to a position adjacent the roof 45 27 of the car as shown by dotted lines in Figure 2, the open folded door being wholly located to one side of the longitudinal center of the car.

Means is provided to hold the folded door in the raised position and to clamp the same against lateral displacement while raised. For this pur-

pose, depending pairs of oppositely facing rigidly connected and recessed jaws 28 are pivoted at 29 to rafters 30 of the car for cooperation with opposed raised grain doors, by engaging the lower edges of their lower sections. A toggle joint 31 connects these pairs of jaws and may be collapsed by a pull cord 32 to swing the pairs of jaws toward each other so as to release and permit lowering of the doors. Other jaws 33 are fixed to the lintel beam 22 to receive the adjacent hingedly connected edges of the folded and raised door sections when the door is forced toward the side of the car by swinging the pairs of jaws 28 apart. The latter operation is effected by use of a second pull cord 34 for straightening the toggle joint, and the cords 32 and 34 are passed around pulleys 35 and 36 to and into the side wall of the car and then inwardly through openings 37 to cord holders 38. The upper door section 11 is held in upwardly swung closed position by suitable means, such as sliding bolts 39 mounted on the door section 11 adjacent its side edges and engageable in sockets 40 provided in the strips 8. The lower door section 10 is provided with a suitable wicket 41 in the lower central portion thereof, and suitable means 42 and 43 are provided for respectively opening and closing the wicket and for securing it in closed position.

In order that the door may be raised with the expenditure of a minimum amount of manual effort, it is nearly counter-balanced by means including weights 44 movable within the side wall of the car and connected to the lower corners of the door by cords 45 which pass over pulleys 46 at the sides and near the top of the door opening, and over other pulleys at 47 carried by the rafters 30 near the longitudinal center of the car.

From the foregoing description, it is believed that the construction, operation and advantages of the present invention will be readily understood and appreciated by those skilled in the art. Minor changes in construction and modifications are contemplated within the spirit and scope of the invention as claimed.

Having described the invention, what is claimed as new is:

1. In combination with a freight car having a door opening in one side wall thereof whose

height is greater than twice the distance from said side wall of the car to the longitudinal center thereof, an inside grain door for substantially closing said door opening including a lower section of nearly the same but slightly lesser vertical dimensions than said distance and an upper section of nearly the same but slightly lesser vertical dimensions than the lower section hinged to the upper edge of the latter to fold inwardly and downwardly against the inner face thereof, said door sections being wider than and extending across the sides of the doorway at the inside of the latter, hollow vertical columns rigidly attached to and spaced outwardly from the sides of the lower door section, said columns extending from near the bottom to the top of said lower door section, telescopic hanger rods including lower sections slidable substantially wholly into the columns and upper sections slidable substantially wholly into the lower sections and hinged to the inside of said side wall of the car above the door opening whereby the folded door may be slid upwardly and then swung inwardly and upwardly to occupy a position beneath the roof of the car wholly between said side wall of the car and the longitudinal center thereof.

2. The construction defined in claim 1, in combination with means for nearly counter-balancing the door including weights vertically movable in the side wall of the car, cords connecting the weights to the lower corners of the lower door section, guides for said cords at the sides and near the top of the door opening, and other guides for said cords directly beneath the roof and near the longitudinal center of the car, said cords extending from the door inwardly and upwardly over the last-named guides and then outwardly over the first-named guides.

CORLISS O. THOMAS.
